AUTOMOBILE FLOOR MAT

Ben R. Jackler, Beverly Hills, Calif., assignor to Custom Crown Mat Co., Inc., Los Angeles, Calif., a corporation of California

Application September 27, 1956, Serial No. 43,109

Term of patent 7 years

(Cl. D9—6)

Fig. 1 is a top plan view of an automobile floor mat, showing my new design; and

Figs. 2, 3, 4 and 5 are fragmentary enlarged cross sections taken respectively on lines 2—2, 3—3, 4—4 and 5—5 of Fig. 1.

The dominant features of my design reside in the portions shown in full lines.

I claim:

The ornamental design for an automobile floor mat, substantially as shown and described.
